WILLIAM GOODCELL, OF BALBOA, CALIFORNIA.

FOLDING BED.

1,224,738.

Specification of Letters Patent.

Patented May 1, 1917.

Application filed August 1, 1914. Serial No. 854,456.

To all whom it may concern:

Be it known that I, WILLIAM GOODCELL, a citizen of the United States, residing at Balboa, in the county of Orange and State of California, have invented a new and useful Folding Bed, of which the following is a specification.

This invention relates to improvements in folding wall beds and the primary object 10 of the invention is to provide a bed in which springs, counterweights or any other counterbalancing devices need not be used, the bed being so constructed that it will substantially balance in different positions, thereby 15 making it an easy matter to open or close the bed.

Another object is to provide means for pivotally supporting the bed which is arranged in such manner as to cause the bed 20 to be moved away from the support therefor, said support being a closet or recess in the wall, whereby free circulation of air about the bed may be had.

Referring to the drawings:

Figure 1 is a vertical sectional view showing the bed folded, dotted lines showing the bed in different extended positions; and

Fig. 2 is a section on line x^2-x^2 of Fig. 1.

Referring to the drawings, 1 designates 30 the casing which is arranged in a recess in a wall, and 2 designates the bed which comprises a bed frame and ordinary essential bed parts, but is free from springs, head or counterweights. Legs 3 are pivoted to the outer 35 ends of the bed. The bed as shown in Fig. 2 of the drawings is of substantially uniform weight throughout and is not specially constructed to provide for more weight at one end or side than at the other.

40 Hangers 4 are pivoted at their upper ends as at 5 to opposite side walls of the casing 1 and at their outer ends are pivoted at 6 to opposite sides of the bed. The pivot points 5 are above the bed and said hangers are substantially two-thirds the length of the bed.

The pivot points 6 are located at points between the inner end of the bed and the transverse center line thereof nearer to the center line than to the inner end of the bed 50 and at points substantially midway of the upper and lower sides. The center of gravity of the bed is located at a point substantially centrally of the ends thereof.

55 Thrust arms 7 are pivoted as at 8 to opposite sides of the casing at their upper ends

and at their lower ends are pivoted as at 9 to opposite sides of the bed. The pivot points 8 are located below the center of gravity of the bed rearwardly of the bed. When the bed is in up position these points are 60 above the pivot points 6 but when the bed is in down position the points 8 are below the pivot points 6. The arms 7 are inclined downwardly and outwardly relative to the casing and the pivot points 9 are located 65 close to the inner end of the bed and to under side thereof at points below the pivot points 6. The dotted line in Fig. 1 designated 10 is drawn horizontally through the center of gravity points of the bed. 70

Assuming that the bed is in up position, as shown in full lines in Fig. 1, to move the bed into open position, it is grasped and pulled out from the casing. When the bed is pulled out of the casing and as soon as it 75 overbalances it will, by its own weight, fall into and balance at a 45° position as shown in dotted lines in Fig. 1. The reason that the bed will fall by force of gravity into such position is that the greater weight thereof is 80 between its outer end and pivot points 6. The bed will remain in 45° position unless the operator gives it a slight downward push whereupon it will assume horizontal position. It will be seen that when the bed is 85 in 45° position the thrust arms 7 are in positions substantially at right angles to the bed and act to overcome the upward and inward movement of the inner end of the bed for this reason. The effect had in this case, 90 is as though a stationary abutment on the casing were caused to temporarily engage the inner end of the bed on the upper face thereof. When the bed is moved from upright into open position, the center of gravity of 95 the bed follows a line which is approximately horizontal, but which has intermediate a downward curve, and the lowest point of this curve is traversed by the center of gravity when the bed is inclined at an angle of 45°. Therefore this will tend to balance the bed as the center of gravity when at its lowermost point in the line of movement thereof causes the weight of the bed to be distributed evenly relative to the pivots. 100 This action, together with the above noted effect provided by the position of the thrust arms relative to the bed, will insure the balancing of the bed in a 45° position. In moving the bed into open position, however, 110

it is best to follow the downward movement of the bed from slightly tilted into horizontal position with a slight pressure from the hand so that the bed will not balance when it reaches the 45° position. During the operation for opening the bed, when the operator follows the downward movement of the bed with pressure from the hand, only a slight resistance is offered the pressure given by the operator when the bed reaches, and as it passes the 45° position. This slight resistance is sufficient to check a swift downward swinging movement of the bed and will prevent the bed from coming down too swiftly and injuring furniture which may be in the way thereof or injuring the operator.

When the bed is being opened the arms 7 swing from a downwardly and outwardly inclined position which is approximately 45° relative to the vertical axis of the bed, outwardly and upwardly into a near horizontal position. It will be seen that the arms do not at any time swing into horizontal position, the inner ends being always higher than the outer ends, thus, when the bed is in horizontal position, the tendency of the inner end of the bed instead of being an upward one is an inward one in a direction substantially in line with the arms 7. This effect is as though abutments were carried on opposite sides of the bed at the pivot points 6 and were caused to engage with stationary abutments located at the outer ends 35 of the arms 7 when the latter are in near horizontal position. Were pivot points 9 higher up upon the sides of the bed with relation to the pivot points 6 and farther away from said pivot points 6, this effect 40 would not be had, but as the pivot points are on the approximate center of gravity line of the bed and as said pivot points 9 are below the center of gravity point and rearwardly of the points 6 the effect above described is had and the bed is balanced in 45 horizontal position. The arms 7 in moving upwardly and outwardly when the bed is being opened cause the bed to be moved out of the casing and this provides for a free circulation of air about the bed. The bed 50 may be swung into closed position by giving it a slight upward pull and following the upward movement with a slight pressure by the hand. When the bed reaches vertical 55 position it is caused to balance in such position since the pivot points 6 of the hangers 4 are then in vertical alignment with the center of gravity of the bed.

With reference to the foregoing description and accompanying drawings, it will be seen that I have provided a bed in which the following advantageous results are accomplished.

1. The bed is caused to project from the 65 casing when open for use.

2. The center of weight of the bed when open is substantially level with the center of weight when closed.

3. The bed will balance in 45° horizontal and vertical position without the use of 70 weights or springs, thus making it possible to open and close the bed quickly, safely and easily.

What I claim is:

1. In a folding bed having its center of 75 gravity located approximately centrally of the ends of the bed, a casing therefor, hangers pivoted to the casing at points over and above the bed, said hangers being pivoted to the sides of the bed at opposite points substantially midway of its upper and lower sides between the inner end of the bed and the transverse center line thereof nearer to the center line than the inner end, thrust arms pivoted to the casing rearwardly of 85 the bed below the center of gravity of the bed and extending downwardly and outwardly from the support, said arms being pivoted at opposite points on the sides of the bed between the pivot points of the 90 hangers with the bed and the inner end of the bed below said hanger pivot points and nearer to the inner end of the bed than to said hanger pivot points, said arms adapted to swing outwardly and upwardly relative 95 to the casing when the bed is opened and being downwardly and outwardly inclined with their inner ends located above their outer ends when the bed is in open position for use.

2. In combination a bed having its center of gravity located approximately centrally of the ends of the bed, a housing for the bed, hangers pivoted to the bed and to the housing, the relative arrangement of said pivots causing the hangers to move from the substantially vertical position when the bed is vertical to a forwardly and outwardly inclined position when the bed is moved from the vertical to the horizontal position and thrust arms pivoted to the bed and to the housing, the relative arrangement of the pivots of the thrust arms causing the thrust arms to move from nearer the vertical to nearer the horizontal when the bed is moved 110 from the vertical to the horizontal and the relative arrangement of the pivots connecting the hangers and thrust arms to the bed causing the thrust arms to move forwardly and upwardly toward the hangers when the 115 bed is moved from vertical to horizontal position, said thrust arms having their inner ends located above their outer ends when the bed is in position for use.

3. In a folding bed, the combination with 125 a bed casing and a bed free from head and counterweights, adapted to lie upright within the casing when in out-of-the-way position and in horizontal position completely out of the casing when in operative position, 130

- of hangers pivoted to the casing above the bed and pivoted to opposite sides of the bed at points approximately midway of the inner side of the bed and transverse median line thereof midway of the upper and lower sides of the bed, and thrust arms pivoted to the casing at points below the center of gravity of the bed and rearwardly of the pivot points of the hangers with the casing, 5 said arms being pivoted to opposite sides of the bed below and rearwardly of the pivots for the hangers with the bed at points substantially midway of the inner side of the bed and the hanger bed pivot points, said arms being inclined downwardly and outwardly when the bed is in out-of-the-way and operative positions and extending out of the casing when the bed is in operative position. 10
4. In a folding bed, the combination with a bed casing and a bed free from head and counterweights, adapted to lie upright in the casing when in out-of-the-way position and to lie completely out of the casing 15 when in operative position, of hangers pivoted to the casing above the bed and to opposite sides of the bed approximately midway of the upper and lower sides of the bed between the inner side of the bed and the transverse median line thereof, and thrust arms pivoted to the casing at points below the center of gravity of the bed and rearwardly of the pivot points of the hangers with the casing, said arms being pivoted 20 to opposite sides of the bed below and rearwardly of the pivots for the hangers with the bed, the lengths of said arms and the 25 positions of the pivots thereof relative to the casing and bed being such that the center of gravity of the bed moves in a substantially horizontal line which has intermediately a downwardly extending curve traversed by the center of gravity when the bed is in approximately 45° position. 30
5. In a folding bed, the combination with a bed casing and a bed free from head and counterweights adapted to lie within the casing when in out-of-the-way position and to lie horizontally completely out of the casing when in operative position, of hangers pivoted to the casing and bed, thrust arms pivoted to the casing and bed and said hangers and thrust arms having lengths and the positions of their pivots such that the center of gravity of the bed moves substantially in a horizontal line which is intermediately downwardly curved, the lowest point of said downwardly curved line being traversed by the center of gravity when the bed is approximately in a 45° position and said thrust arms being substantially at right angles to the bed when the latter is in 45° position, whereby the effect of the positions of the thrust arms relative to the bed and casing, together with the position of the center of gravity, will cause the bed to balance in an approximately 45° position. 35

In testimony whereof, I have hereunto set my hand at Los Angeles, California, this 24th day of July, 1914.

WILLIAM GOODCELL.
